(57) **CLAIM**

The ornamental design for a fitting tool for a mounting object on roof, as shown and described.

DESCRIPTION

FIG. 1 is a front elevational view of a fitting tool for a mounting object on roof showing my new design, a rear elevational view being symmetrical therewith;
FIG. 2 is a right side elevational view thereof;
FIG. 3 is a left side elevational view thereof;
FIG. 4 is a top plan view thereof;
FIG. 5 is a bottom plan view thereof;

FIG. 6 is a perspective view 1 showing the front, top, and right side views thereof; and,

FIG. 7 is a perspective view 2 showing the front, top, and left side views thereof.

The broken lines represent environmental structure only, and form no part of the claimed design. The dot-dash lines represent the boundaries of the claimed design and form no part of the claimed design.
